UNITED STATES PATENT OFFICE.

LOUIS G. MILLER AND EDWARD C. LONG, OF WESTMONT, PENNSYLVANIA.

CAR-DOOR CONSTRUCTION.

1,319,786.

Specification of Letters Patent. Patented Oct. 28, 1919.

Application filed March 5, 1919. Serial No. 280,786.

To all whom it may concern:

Be it known that we, LOUIS G. MILLER and EDWARD C. LONG, both citizens of the United States, and residents of the borough 5 of Westmont, county of Cambria, and State of Pennsylvania, have invented certain new and useful Improvements in Car-Door Constructions; and we do hereby declare the following to be a full, clear, and exact description of the invention, such as will enable others skilled in the art to which it 10 pertains to make and use the same.

Our invention relates to improvements in car door construction with particular reference to the support and pivot of drop doors of gondola, hopper and other cars.

One of the objects of our invention is to provide a simple and cheap construction whereby the edge of the door which is adjacent the hopper sheet, is firmly supported and at the same time adapted to revolve about or upon said support for the purpose of opening and closing the door, while the supporting portion itself which is attached 20 to the hopper sheet aids in strengthening and stiffening the same, thus obviating separate supporting and stiffening members.

Having thus given a general description of our invention, we will now, in order to 30 make the matter more clear, refer to the annexed sheet of drawings forming part of this specification and in which like characters refer to like parts.

Figure 1 is a vertical sectional elevation 35 through the lower portion of a hopper car showing the application of our invention. Fig. 2 is a vertical section on a slightly enlarged scale of one form of our car door construction. Figs. 3, 4 and 5 are views 40 similar to Fig. 2, but showing modified forms of our construction using different shapes of stiffening and supporting members as illustrated. Fig. 6 illustrates in side elevation a pressed metal door support of 45 general Z-shape. Fig. 7 is an end elevation of the door support illustrated in Fig. 6. Figs. 8 and 9 illustrate in sectional elevation the hinge or pivot end of one form of our car door. Fig. 10 is a plan and 11 a sectional 50 elevation of another form of the hinge or pivot end of our car door. Fig. 12 is a side elevation of one form of our car door retaining bar and Fig. 13 illustrates another form of same.

Referring now to the characters of refer-

ence on the drawings: 1 represents the portion of the car in general adjacent to the dump doors thereof, 2 are the hopper sheets, 3 is our car door support shown as a rolled Z-bar which is securely riveted to the hopper plates by one of its flanges with its web projecting downwardly and its other flange projecting toward the door opening in such a way as to serve as a support for the end of the car door, as illustrated. The car in 65 general is 4, the spreader bars secured to the car doors are 5, these spreader bars being adapted to be secured to the two adjacent doors and to which the door lifting and lowering mechanism (not shown) is attached. 70 The car door is preferably of pressed metal and is provided with a curled hinge-end 6, as illustrated, this end being formed of approximately semicircular section, the inside of which is adapted to fit over the hinge bar 76 or pin 9 and the outer surface of which is adapted to rest upon, turn upon, and be supported by, the flange of the door support. The hinged end of the car door is provided with notches 7 adapted to receive the down-turned ends of the hinge bar 10, as illustrated particularly in Fig. 12, this end being provided with nuts 11 to secure the hinge bar in place and the ends 10 may be riveted over the nuts to add to the security thereof. 85 The portions adjacent the notches 7 are reinforced by integral projections 8.

As illustrated in Fig. 3, 12 is another slightly modified form of hinge bar which is riveted in place by the rivet heads 13 but 90 is otherwise similar to that illustrated in Figs. 2 and 12; while 14 is the hopper sheet extension adapted to project over the bent end of the door, as illustrated, to form a closure therefor and to prevent the lading 95 from fouling the hinge, and this is equally true of the other constructions shown in which, however, the hopper sheet projections are slightly shorter.

As illustrated in Fig. 4, 15 is a hopper 100 sheet stiffener or door support of channel section instead of the Z-bar illustrated in Figs. 1, 2 and 3, and 17 are perforated eye-ends of another slightly modified form of retaining bar 16 further illustrated in Fig. 105 13, which bar is adapted to be secured in place to the lower flange of the channel 15 by means of rivets 18.

As illustrated in Figs. 6 and 7, 19 is a door support and hopper plate stiffener formed of 110

pressed metal approximately of Z-section and provided with depressions or corrugations 20 therein for the purpose of stiffening the same, and 21 are offset portions of the 5 curved hinged end of the door adapted to stiffen the same and form bearings therefor, as illustrated in Figs. 8 and 9.

As illustrated in Fig. 5, 22 is another slightly modified form of door support of 10 pressed steel provided with a lower supporting portion or flange 23 and an upper portion 24 secured to the door hopper plate 2.

Our door support and hopper plate stiffener is adapted to be secured to the lower portion of the hopper sheet and thereby to strengthen and stiffen the same, thus obviating the necessity of special hopper sheet stiffeners and the integral hinge construction of our door end in combination with the supporting and stiffening member obviates the use of the usual forged strap hinges which are generally heavy and expensive. Our construction, therefore, 25 produces to lightness and economy of construction, maintenance and repair.

Our construction is such that the outer curved end of the door rests upon and is adapted to be rotated upon the lower flange 30 of the door support and stiffening member, while the function of the hinge bar is principally to retain the door in position and to guide the curved end during the rotation of the door.

Although we have described and illustrated our invention in considerable detail, we do not wish to be limited to the exact and specific details thereof, as shown and described, but may use such modifications in, 40 substitutions for, or equivalents thereof, as are embraced within the scope of our invention, or as pointed out in the claims.

Having thus described my invention, what we claim and desire to secure by Letters 45 Patent is:

1. In a car, a door supporting member secured to and adjacent the edge of the hopper sheet and provided with a flange adapted to directly receive and support the 60 end of the door, and means for retaining said end in rotatable position thereon.

2. In a car, a door supporting member secured to the hopper sheet adjacent the lower edge thereof comprising a flanged 65 member, one flange of which is secured to the hopper sheet and the other flange spaced apart therefrom and adapted to directly support a door provided with a curved end

and means for retaining said end in position thereon.

3. In a car, the combination with the hopper sheet, of a flanged member secured thereto and provided with a door supporting portion below said sheet adapted to directly receive and support a door provided with a curved end, and a retaining bar located within said curved end and secured to said supporting flanged portion.

4. In a car, a flanged door supporting member secured to the hopper sheet provided with a flange spaced apart therefrom and adapted to support the door, the end portion of which is offset and bent approximately in the form of a semi-circle with its convex side resting upon and supported by 75 said flange, and means for retaining said curved portion in rotatable position thereon.

5. In a car, a supporting member secured to the hopper sheet provided with a flange spaced apart therefrom and adapted to directly support the end of a door, provided with an offset and curved end approximately in the form of a semicircle, a round bar of U-shape the intermediate portion of which is fitted within said curved end and 85 the end portions secured to the flange aforesaid.

6. In a car, a door supporting member secured adjacent the lower edge of the hopper sheet, comprising a bar having a 90 web portion with upper and lower flanges extending at angles thereto, one of said flanges being attached to the hopper sheet; a retaining bar secured to the other flange; a car door having a curved end, the convex 95 portion of which is supported upon the latter flange and maintained in place by a retaining pin, the body of which is located within the cavity of said curved end.

7. In a car, a door supporting member secured to and adjacent to the edge of the hopper sheet, comprising a bar having a web portion with flanges extending from each edge of the web portion, one of the flanges being secured to the hopper sheet; 105 a door having its upper edge of partially hollow cylindrical curvature the convex side of which is supported on the upper portion of the other flange, and means co-operating with the concavity of said door edge for 110 retaining the same in rotatable position thereon.

In witness whereof we hereunto affix our signatures.

LOUIS G. MILLER.
EDWARD C. LONG.
